UNITED STATES PATENT OFFICE.

ALFONSO ORZO, OF NEW YORK, N. Y.

DESIGN FOR A COSMETIC JAR.

Application filed December 7, 1926. Serial No. 19,956. Term of patent 14 years.

To all whom it may concern:

Be it known that I, ALFONSO ORZO, a citizen of the United States, residing in New York city, borough of the Bronx, county of Bronx, and State of New York, have invented a certain new, original, and ornamental Design for Cosmetic Jars, of which the following is a specification, reference being had to the accompanying drawing, which is a perspective view of a cosmetic jar showing my new design.

I claim:

The ornamental design for a cosmetic jar as shown.

ALFONSO ORZO.
